MUSICAL WIND INSTRUMENT

Filed Dec. 4, 1928

2 Sheets-Sheet 2

UNITED STATES PATENT OFFICE

HARRY BERNARD, OF CHAMBERSBURG, PENNSYLVANIA

MUSICAL WIND INSTRUMENT

Application filed December 4, 1928. Serial No. 323,663.

This invention relates to improvements in musical wind instruments of the type having lateral air vents from which different tones are emitted, such as oboes, flutes, saxophones, clarinets, and etc., and particularly refers to a wind instrument having the normal series of lateral vents for the production of its full gamut and an additional number of lateral vents organized with and forming part of the whole series of tone emitting vents, to allow a player to start the production of musical gamuts at more than one place, in a manner similar to that followed by a piano player in executing a change of octaves.

This application particularly relates to the subject matter disclosed in my prior application for Letters Patent, Serial 634,831, filed April 26th, 1923, on musical wind instruments.

In all musical wind instruments previously invented complete chromatic scales could not be easily executed, owing to the fact that all semi-tones could not be produced except with individual keys, as in the case of key operated wind instruments like the organ or key operated string instruments like the piano, as a part of the normal playing movements of the player of the musical wind instrument.

Owing to the rapid succession with which the different musical tones of a composition must be produced in the manual playing of a portable wind instrument of the type embraced herein, perfect organization of the vents employed for the selective production of the full scale of full tones and semi-tones, with the view of reducing the sweep required in controlling hand and finger movements, to provide positive and easy selection, to permit of the production of music in perfect time, without distortion of tones, is required. To accomplish this, with all the requisite mechanical control necessary for selective vent operation, I conceived the construction, unity, successive disposition and operating means disclosed in this application.

By the aid of my improved musical wind instrument it is made possible for a player to manipulate his or her fingers over a group of tone emitting vents, and still operate with

the same routine after a change of gamut location as described. By this improved organization of air vents and the controlling mechanism therefor, proper execution of the art is made easier for the student and the professional, and each player may then well concentrate upon the perfection of musical skill, rather than be diverted with the work of training the fingers and arms to gain speed and selectivity with instruments of inferior design and incomplete equipment for the production of perfect music.

In addition to the above objects I also wish to provide a saxophone having all of the tone emitting vents located in the horn along an approximately uncurved length thereof, and also to provide a horn bell on the instrument extending but slightly at a relatively low rising angle from the normally inclined horn or instrument, (when in the position held by a player in playing) which will constitute a liquid trap to collect and hold the water drained through the horn by the condensation of moisture from the breath of the player, and by mouth leakage, so that the knees of the player will be protected against wetting or saturation from the usual discharge of the water.

A further object of the invention is the provision of a spring for operating the individual keys for each vent, which is constructed with companion legs designed to lie in non-parallel planes, and to have a clasping or retaining action upon the material through which they are inserted, with the longer of the two legs exerting tension upon the vent controlling key to move it to or hold it open position, or otherwise actuate it.

A still further object of the invention is the provision of a means for controlling certain of the upper group of vent controlling keys, from the lower end of the instrument.

A still further object of the invention is the provision of a musical instrument with flat key valve seats and a moisture proof, yielding, valve pad for each valve seat, together with an air-tight housing for the slide valve, particularly the upper part thereof, to insure a concentration of the air stream set in vibrating motion by the player in the horn

passage upon the various zones governed by the vent keys, so that the anticipated acoustic properties or results will be accomplished and the instrument will continue through long service to function as desired.

- 6 A still further object of the invention is the provision of musical wind instrument of the type embraced with a series of normal tone emitting vents and a series of intermediate vents, together with a common valve constructed and controlled so that chromatic scales can be executed upon the instrument, with the least effort and greatest possible technique.
- 10 The musical wind instrument disclosed by this application is equipped with a system of tone emitting vents and selectively operating controls therefor, by means of which the player may realize the gamut progression.
- 15 With the above and other objects in view the invention consists in certain new and useful combinations, constructions, and arrangements of parts, clearly described in the following specification, and fully illustrated in the accompanying drawings, in which:—

Fig. 1 is a side elevation.

Fig. 2 is a longitudinal sectional view, on an enlarged scale, showing the slide valve in one position with relation to the tone emitting vents of the horn.

30 Fig. 3 is a fragmentary longitudinal sectional view showing the same slide valve in another position, with reference to a part only of the same vents, the balance being omitted for simplification only.

Fig. 4 is a plan view of the horn showing the housing of the slide valve and the vents of the housing, with certain operating parts removed to expose the construction of the 40 housing and the system of vents.

Fig. 5 is a transverse sectional view taken on line 5 of Fig. 1, showing the mounting of one of the vent controlling keys and its spring, and also showing the detail construction of the housing.

Fig. 6 is a detail plan view of one of the operating elements, or lever rods.

Fig. 7 is a detail plan view of another rod, showing the two positions in which the terminal button of the rod may be placed.

Fig. 8 is a detail transverse sectional view showing the mounting of an operating spring.

Fig. 9 is a detail view in longitudinal section, on an enlarged scale, showing the closed end of the housing which houses the upper end of the slide valve and positively prevents leakage of the vibrating air stream at the point of its maximum intensity.

Fig. 10 is a detail fragmentary plan view, on an enlarged scale, showing two vent keys and the relation of the shiftable button of the operating lever thereto.

Fig. 11 is a similar view of two other keys.

Fig. 12 is a detail view in enlarged longitudinal section showing the angle of inser-

tion of the U-shaped spring used for actuating the vent key.

Fig. 13 is a detail fragmentary view, partly in section, showing the U-shaped spring and the non-parallel disposition of the legs thereof.

Fig. 14 is a detail sectional view showing the angular disposition of the holes through which the spring is inserted.

Fig. 15 is a detail sectional view of a pillar.

Fig. 16 is a detail transverse sectional view of the horn bell, showing the yoke which carries the slide valve lever.

Fig. 17 is a detail transverse sectional view through the mouth tube, showing the improved reed clamp for the mouthpiece.

Referring to the accompanying drawings A designates the horn of a saxophone, which is formed with a short horn bell B, located at its lower end, while the mouthpiece is indicated at C.

The upper end of the horn is provided with a short, slightly tapered inlet portion Ca, which is disposed at a convenient angle to the body of the horn, which extends downwardly, in the normal playing position, gradually increasing in diameter by reason of its tapered construction, until it connects with the horn bell B. This horn bell is disposed at a slight upward angle, and is relatively short, so that it does not obstruct the zones of playing movements executed in operating any of the keys controlling the lateral vents of the instrument.

The lateral vents are all located in the horn between the curved upper end portion Ca and the short horn bell B, in a series disposed in a straight line and which extend through the upper side wall portion of the horn. This series of vents D are shown to be eighteen in number, and are designated 1 to 18, reading from the upper end of the horn downwardly.

A housing 19 is attached positively to the side of the horn. This housing is preferably constructed from a single sheet of metal, bent upon itself to form a box-like tubular structure, with the upper end of this structure provided with an end wall 19a which positively closes the chamber of the housing against all air leakage. This housing is provided with a series of arms 20, which project laterally thereof and are shown to be formed from the bottom wall 19b of the housing. These arms are curved or extended outwardly toward the plane of the outer face of the housing and are spaced at their ends from the adjacent side wall of the housing. All joints are sealed by solder or otherwise against leakage of air through the housing, but the bottom wall 19b and the top wall 19d of the housing are formed with vent openings registering with the vents 1 to 18, inclusive, of the horn.

In the valve chamber 21 of the housing 19

the slide valve 22 is arranged to reciprocate. This slide valve is a moderately thin piece of sheet metal, in the nature of a strip of metal and snugly fits in the chamber against the top and bottom walls and the side walls thereof. The lower end of the slide projects below the lower end of the housing and is provided with a bearing hole or element 22a.

The slide valve 22 is formed with a series of transverse openings adapted to register with one or more of the vents of the horn and the associated openings of the valve housing. The vent openings of the housing and the horn are shown to be small circular openings, though any other suitable shape could be used, while some of the openings of the slide valve are circular, while others are elongated, so as to give a varying valving action.

The valve opening 1a is of a size equal in shape and length to that of the vent opening 1 of the housing and horn; the next valve opening 2a is shown to have the same width but twice the length as the vent opening 2 of the horn and housing. The valve opening 3a is of the same size, length and shape as the vent opening 3. The next valve opening 4a is of the same size, shape and length as the vent opening 4 of the horn. The next succeeding valve opening 5a has twice the length of the vent opening 5, and the same width. The following valve opening 6a is of the same length and width as the vent opening 6. The valve opening 7 is of the same size and length as the vent opening 7. The valve opening 8a is twice the length but the same width as the vent opening 8. The valve opening 9a is the same length and width as the vent opening 9. The valve opening 10a is the same length and width as the vent opening 10. The valve opening 11a is twice the length but the same width as the vent opening 11. The valve opening 12a is the same length and width as the opening 12. The valve opening 13a is the same length and width as the vent opening 13. The valve opening 14a is twice the length but the same width as the vent opening 14. The valve opening 15a is the same length and width as the vent opening 15. The valve opening 16a is of the same length and width as the vent opening 16. The valve opening 17a is twice the length, but the same width as the vent opening 17. The last valve opening 18a is of the same length and width as the vent opening 18.

The valve is arranged to have two positions, one being illustrated in Fig. 2 and the other in Fig. 3. In the former figure the vents 1, 4, 7, 10, 13, and 16 are shown to be closed, while the vents 2, 3, 5, 6, 8, 9, 11, 12, 14, 15 and 18 are shown to be open. When the slide valve moves downwardly a distance equal to the length of any of the vent openings, and a slight addition thereto, the vent openings 1, 4, 7, 10, 13, and 16 will be opened;

while the vent openings 3, 6, 9, 12, 15, and 18, will be closed. At the same time the vent openings 2, 5, 8, 11, 14, and 17 will remain open while the valve is in both of these positions and while moving from one position to the other.

The slide valve is shifted from one position to the other by means of a hand operated lever 24, which is pivoted at 25 to the yoke 26, attached to the horn bell in any suitable manner. This lever has a pointed inner end 24a, which engages the bearing hole or element on the lower end of the valve, and is provided with a closed loop 24b finger hold, whereby the player may readily actuate the same while playing. A spring 22b is connected to the slide valve and acts to hold the same in its initial position shown in Fig. 2.

A rod 28 extends through the arms 20 and on this rod a series of flat key valves 29 are mounted by means of the elongated eyes 29a. Each of these valves is formed with a pocket which carries a pad 29b of material known under the trade-name of Artgum, and sold extensively in stationery stores for erasing and cleansing paper and fabrics, etc. This material is not composed of rubber and does not break down, decay, or disintegrate from the effect of moisture or water, or oil. I have found by long experience that it is particularly adapted for use as a pad for completely closing the vents of musical instruments. These instruments are frequently oiled and experience has shown that rubber cannot be relied upon, as the oil used soon renders them useless and as leakage develops the musical instrument significantly fails to give proper service. But I have also found that the successful use of these valve pads involves a frank departure from current and long sustained practice in designing and making musical wind instruments. It has been the common and traditional practice to cup tip the material surrounding the valve opening or vent of the horn and use this as a valve seat, but such a valve seat would rapidly break up the relatively fragile cushioning material known as Artgum, which I employ. I have therefore designed a flat valve seat, formed by employing a uniform flat face on the housing wall and providing the vent openings in this flat wall. The valve pads of Artgum engage this flat surface and experience has shown that they will last indefinitely, without special attention, and will not break up under the action of the oil and mouth juices to which they are exposed.

The key valves are engaged by U-shaped wire springs 30, one leg 30a of which is longer than the other leg 30b. These legs converge slightly toward each other, so that they will have a clasping action upon the material through which they are inserted, as shown in the drawings. The housing is provided with inclined holes and both legs of the spring

are pushed through these holes, so that the longer leg 30a will engage the underside of the adjacent key valve, the shorter arm serving to hold the spring in place, by a clasping action. I also use diverging legs on the 5 springs.

The lower end of the rod 28 is equipped with an angular handle 28a and the upper end carries a small arm 28b on which the 10 small button or finger 28c is pivoted. This button or finger is designed to engage one of the upper key valves and to actuate this valve when the rod itself is turned by means of the handle on its lower end. By turning the button or finger the opposite key valve will be 15 engaged and it will be actuated when the rod 28 is turned. This pivotal support thus gives the player a choice of either control, while the rod itself provides means for operating from the lower end or bell end of the horn a key valve on the upper end of the instrument, and time which would be consumed in moving the hand from the bell location to the mouth end of the instrument is conserved 20 25 and the player has better control over the production of tones in correct musical order. The button or finger is designed to bear against a spring opened valve on its outer surface, while it would bear against the inner 30 surface of a spring closed valve. When the rod 28 is rocked the finger will hold the valve or key which it engages to its seat so that the vent commanded by it will be held closed. In the arrangement illustrated, the player 35 would have the choice of either of the two uppermost keys, but once the button or finger is shifted to alignment with one of these keys it would only operate to hold this key closed.

On the extreme upper end of the housing 40 an arm 32 is fixed, which is equipped with a terminal pin 33. On the upper portion of the rod 28 an additional lever rod 34 is mounted to rock; it being mounted on the rod 28 by means of integral eyes 34a and 34b. This 45 lever rod 34 is equipped with a lateral lug 35 which is engaged by a spring 36, the opposite end of the spring being engaged with the pin 33.

The lug 35 is designed to bear against the 50 uppermost valve key and the tension of the coil spring 36 is exerted to maintain this valve locked against the opening action which its own U-shaped spring tends to produce. By rocking the lever this spring is thus allowed 55 to function and the valve will open. For this purpose the spring 36 must be able to overpower the individual spring of the valve key.

As an auxiliary locking means I provide 60 a small lever 37, which is mounted upon the pillar 38 at the upper end of the horn. This lever is designed to be shifted upon the pillar by manual operation at its location, while the lever 34 permits of operation at a point distant from the key operated, or locked against 65 operation.

The slide valve has a limited movement from the position shown in Fig. 2 to the position shown in Fig. 3. The operating lever which shifts this valve back and forth, together with its cooperating spring, is provided with a projection 24c, which is designed to limit the sliding movement of the valve, and which abuts on the horn bell for this purpose when the lever is rocked against the tension of the spring. 70

It is noted that every third valve opening is elongated so that it will hold the vent registering with it open in either of the two positions which the valve can be shifted to. These vents are thus arranged to enable the 75 player to execute chromatic scales. As shown the vents are arranged in clusters of three to each group, each cluster or group of three vents being controlled by a single spring actuated key; and the central vent of each such cluster being the one in registration with the 80 elongated opening of the slide valve. When the upper one of the three vents is closed the lower one is open, and when the lower one is closed the upper one is open, while the intermediate of middle vent will always be open, with the valve key in open position, at all times. In this way I have found by careful musical tests that a semi-tone is emitted by the intermediate opening of each cluster, 85 or of each couple of full tone vents. The precise tuning which will be given to the series of vents will vary with the standards of the manufacturer, and does not call for any restrictions in this description. The plan disclosed is merely typical of one adaptation of 90 the invention. 100

In Fig. 17 I show an improved reed clamping mouthpiece, which includes the frame or case 40, which is formed with opposed lugs 105 41 in which the trunnion or bearing pins of the eccentric rollers 42 work. These eccentrics are shifted radially by means of the arms 43, so that various degrees of pressure 110 may be applied on the reed clamped between the eccentrics and the case. 115

It is understood that various changes of detail, structure and relation may be resorted to, within the compass of the protection set forth in the claims, without departing from the spirit and scope of the invention, herein declared. 120

Having described my invention I desire to secure by Letters Patent:—

1. A musical wind instrument provided 120 with an air passage and a vent discharging laterally thereof, a key for controlling the vent, and a U-shaped spring having each of its legs anchored through the body of the instrument and one of said legs bearing 125 against said key to hold the same in one position.

2. A musical wind instrument provided 130 with an air passage and a vent discharging laterally thereof, a key for controlling said

- vent, and a U-shaped spring having both of its legs inserted through openings in a portion of the body of the instrument, and one of its legs bearing against said key to hold the same in one position.
3. A musical wind instrument having an air passage and a plurality of vents discharging laterally from the air passage, said air passage having an inlet, said instrument having a plurality of vents located near the inlet, keys for controlling the last named vents, and means for restraining said last named keys.
4. A musical wind instrument having an air passage and a series of vents discharging laterally thereof, keys for controlling said vents, said air passage having an inlet and said vents being spaced successively from said inlet, and means for restraining the keys of said vents nearest the inlet, the keys of the other vents being free of all restraint to be operated at all times.
5. A musical wind instrument provided with an air passage and having a housing provided with vents discharging laterally of the housing, said air passage having an inlet, a valve element in said housing to control all of said vents, said housing having a closed end located near said inlet, whereby air admitted through the inlet by a player is forced to discharge laterally through the vents only.
6. A musical wind instrument provided with an air passage and having a housing provided with vents discharging laterally of the air passage and housing, said air passage having an inlet, a valve element in said housing to control all of said vents, said housing having a closed end located near said inlet, whereby air is forced to discharge laterally through the vents only, said valve being constructed to operate said vents to produce semi-tone changes only.
7. In a musical wind instrument having a row of lateral vents, keys for controlling said vents, key-springs for said keys having reverse-turn anchorage with said instrument to engage the keys, and means near one end of the row of vents for controlling keys near the other end of the row of vents.
8. A musical wind instrument having a valve housing provided with a series of vents and consisting of a strip of sheet metal folded upon itself to provide a box-like structure, one edge portion of the material of said housing being extended to provide a series of key supporting arms spaced from each other and projecting from the housing.
9. A musical wind instrument having a series of vent controlling keys disposed in lined relation to each other, and means operable from one end of the series of vents for actuating keys controlling vents of the opposite end of the series.
10. A musical wind instrument having a series of vent controlling keys, supports for said keys, and a turnable pintle rod extending through said supports and keys and provided with means carried by said rod to operate one of said keys when said rod is turned.
11. In a musical wind instrument having its fundamental tones principally emitted through couplet vents and associated intermediate vents throughout its vent alignment, means for closing one or the other of the said couplet vents, and means whereby the intermediate vent of each couplet is left open.
12. In a musical wind instrument provided with tone couplet vents throughout its lateral vent alignment, and intermediate vents associated with the couplet vents, and a slide for controlling said couplet vents and intermediate vents.
13. In a musical wind instrument with tone couplet vents and an intermediate vent alignment, a slide controlling said couplet vents, and means whereby said intermediate vent is held constantly open to co-act with one of the other couplet vents, said means consisting of an elongated aperture in said slide adapted to align at all times with said intermediate vent.
14. A musical wind instrument having a series of lateral vents and keys for controlling the vents disposed in lined relation to each other, and means operable from one end of the series of vents for selectively controlling vents of the opposite end of the series.
15. A musical wind instrument with tone couplet vents and an intermediate vent associated therewith throughout its lateral vent alignment, a slide for controlling said couplet vents, and means whereby said intermediate vent is constantly open to co-act with one of the other of the couplet vents.
16. A musical wind instrument having a horn provided with a housing having a series of flat valve seats, said horn having lateral vents, said lateral vents being arranged in groups of two for emitting fundamental tones and an intermediate vent for each group of two vents, and a slide movable in said housing for alternately opening and closing each one of the two vents of each of said groups and at the same time maintaining said intermediate vent open, a key for each of said groups of two vents for fundamental tones and one intermediate vent for semi-tones, and a pad carried by each key composed of Artgum, said pad being adapted to seat snugly on its valve seat to maintain non-leaking control of its cluster of three vents.
17. A musical wind instrument consisting of a horn provided with a series of lateral vents disposed in a continuous row, said vents being arranged in clusters of three vents, the intermediate of said three vents being designed to emit semi-tones, and a common valve control for said vents arranged to alternately

open and close two vents of each cluster of vents but to maintain normally open the intermediate vent of each cluster, and a spring actuated key for each cluster of vents.

18. A musical wind instrument having a horn provided with a series of lateral vents arranged in a continuous row, keys for controlling said lateral vents, springs for moving said keys in one direction only, a lever for selectively restraining certain of said keys, and a second lever for restraining a key not restrained by the first lever.

19. A musical wind instrument having a horn provided with a series of lateral vents arranged in a continuous row, keys for controlling said lateral vents, springs for moving the keys in one direction only, a lever for moving certain of the keys against the action of their springs, and a lever equipped with a spring for actuating the same to hold one of said keys in one position against the action of its own spring.

Signed at Brooklyn, in the county of Kings, and State of New York.
